by G. H. Remington
Atty.

UNITED STATES PATENT OFFICE.

FRANK W. GRISWOLD, OF PROVIDENCE, RHODE ISLAND.

TIME-CHECK REGISTER.

SPECIFICATION forming part of Letters Patent No. 313,934, dated March 17, 1885.

Application filed October 10, 1884. (No model.)

To all whom it may concern:

Be it known that I, FRANK W. GRISWOLD, a citizen of the United States, residing at Providence, in the county of Providence and

5 State of Rhode Island, have invented certain new and useful Improvements in Time-Check Registers; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 My present invention relates to time-check registers; and it consists, first, of a double-tube conductor suitably mounted and adapted to receive rotary motion, the head or receiving end thereof having a central opening, 20 around which is formed a spiraling V-shaped depression, its lowest portion ending in an opening eccentric to the center, each of said openings terminating in a tubular connection, which is fixed at a suitable angle to the axis 25 of rotation, whereby time-checks deposited within the receiver at any time are conducted to their respective tubes and thence to a receptacle beneath.

The invention consists, secondly, of two 30 non-interchangeable circular checks, one of which is provided with a central conical projection, the other having a central convex projection, the latter being of less height but of greater diameter than the former projection.

35 The invention consists, thirdly, of a "station" composed of two cylinders or chambers, each having a mouth-piece detachably secured thereto, provided with an aperture or slit, which is cut away centrally and transversely 40 to allow its respective check to pass within the station. By means of the removable and interchangeable mouth-piece the stations are readily adapted to be made right and left at will.

45 The object of this invention is to enable a workman to deposit his "in" or "out" check at any time within the station, from whence it is conveyed to the conductor, the latter being actuated by a suitable clock-train or other 50 mechanism, which insures the delivery of the checks within the proper compartment of the stationary drawer beneath, the invention be-

ing an improvement upon the time-check register patented in the United States by Phillips and Griswold, August 22, 1882, numbered 262,979.

In the accompanying sheet of drawings, Figure 1 represents a general view of a system embodying my invention, the case, &c., of the register being shown in section. Fig. 60 2 is an enlarged sectional elevation of the revolving conductor as in use. Fig. 3 is a top view of the same. Fig. 4 is a partial sectional view as cut through *xx* of Fig. 3. Fig. 5 is a front view of the double station showing the 65 check-receiving apertures of the removable mouth-pieces, each being provided with a central enlargement corresponding in shape to the projection formed on the check adapted to be placed therein, and also showing a swinging gate adapted to cover the apertures. Fig. 6 is a top view of the same. Fig. 7 is a vertical central sectional view through *oo* of Fig. 5. Fig. 8 represents enlarged views of the checks, corresponding to the respective slits 75 or apertures of the station; and Fig. 9 is a cross-sectional view (enlarged) of the bridge or tie connecting adjacent openings of the stationary plate or partition, the upper surface being rounded to facilitate the entrance of the 80 checks, the view being taken on line *w w* of Fig. 2.

The following is a description of the invention and the manner of its operation:

A is the head or receiving end of the conductor, which approximates an inverted cone in form. Extending downwardly therefrom is a spindle, *a*², suitably mounted, upon which is secured a driving gear-wheel, *g*, which imparts rotary motion to the conductor. The 85 top central portion of the head consists of the circular opening *a*, surrounded by the annular partition *a*⁴. Said opening extends downwardly, and diverging from the axial line terminates in the tube *a*, as fully shown in Figs. 90 1 and 2. Between the partition *a*⁴ and the exterior of the head is formed an annular space, *A'*, which is nearly V-shaped in its cross-section. The lower surface, *a*⁵, thereof extends nearly around the interior of the head in the 95 form of a quick-receding volute or spiral and terminates in the opening and tube *b*, parallel with the tube *a*, before described. A wedge-shaped tie, *a*⁶, formed within the space *A'*,

serves to deflect the checks directly into the opening b , or else to cause them to roll along the inclined surface a^5 , which in turn leads to the tube b .

5 H designates the holder or box within which the said conductor and its operating mechanism is suitably arranged and mounted. K' is a removable drawer provided with a series of check-boxes, K. A stationary plate or partition, u, located directly over said box, is provided with a corresponding series of openings, v, each connected by a tie, u', which is well rounded upon its upper edge. (See Fig. 9.) The lower end of the conductor-tubes a b are connected by plates z z , which extend beyond the end of the tubes, as fully shown in Fig. 2. With this system of time-keeping two time-checks are requisite, the same to be dropped respectively into the tubes a and b , 15 the former tube representing the time when the workman ceases labor and leaves the room and the latter representing the time when he arrives to resume his labors. These checks are termed "out" and "in," and are used accordingly.

It is obvious, in order to avoid mistakes, that the checks be made non-interchangeable. I therefore provide the "out" check D, Fig. 8, with a central raised portion, d, having a convex form, and the "in" check E is provided with centrally-raised projection, e, the latter being conical in shape and of less diameter than the projection d , but being of greater height. These checks are made from sheet 35 metal, the centers d e thereof being struck or swaged, as common. The station consists of the chambers 0 and 1, provided with the detachable mouth-pieces 0' 1', respectively, each having a slit or aperture adapted to receive its corresponding check, the center of the slit d' being cut away at d^2 , both top and bottom, to conform to the projection d of the check D, (see Fig. 5,) the center of the slit e' in the mouth-piece 1' having a V-shaped notch, e^2 , therein, also top 40 and bottom, which in turn conforms to the cone e of the check E. By means of said double notches the respective checks are adapted to be placed within the mouth-piece either side up.

50 In Fig. 1 the system is shown complete, the double station being placed at a convenient height above the floor f , and connected, by means of tubes a' b' , to the cover B of the holder. This cover is provided with a central opening, a' , its lower edge projecting into the space a of the conductor A. A similar and parallel projection, b' , extends into the space A' , all as clearly represented in Fig. 2.

60 Assuming now the system shown in Fig. 1 to be employed, which embodies the present invention, the operation would be as follows: An operative being first supplied with the time-checks, upon his arrival deposits a 65 check, E, within the mouth-piece 1' of the station, from whence it falls into the tube b' , and into the head A of the revolving re-

ceiver, thence down the conductor-tube b , through an opening, v , of the partition u , the check finally resting within a compartment, K. At the close of work the operative deposits a check, D, within the mouth-piece o' , from whence in turn it falls down the tube a' into the center opening of the receiver, and into the conductor-tube a , which guides the 75 check into the compartment corresponding to the position of the said tube a at the time.

It is obvious that checks dropped within the stationary tubes a' b' at any time will be certain to pass into the head or receiver 80 of the revolving conductor, from whence they readily roll into the respective tubes a b , and into the stationary receptacle beneath.

Having thus described my invention, what I claim as new, and desire to secure by Letters Patent, is—

1. In a time - check register, the double check-conductor herein described, the head thereof having a central opening, a , around which is formed an annular space, its bottom 90 surface having the form of a quick-receding volute or spiral and terminating in the eccentric or side opening, b , both of said openings a b , extended downwardly, forming the conductor-tubes, the head being further provided with a center spindle or arbor, thereby adapting the conductor to be mounted and rotated within a register, substantially as shown, and for the purpose set forth.

2. The combination, in a time - check register provided with the rotating double conductor herein described, of the double station 0 1, each chamber thereof provided with a removable and interchangeable mouth-piece having an opening or slit adapted to receive time - checks, with stationary tubes connecting the station and register, substantially as shown, and for the purpose set forth.

3. In a time-check register, the double station herein described, having interchangeable 110 and apertured mouth-pieces, in combination with the non-interchangeable metallic checks E D, each having a central projection, the center e of the former check being conical, and that of the latter being convex, said projections being so proportioned as to render the checks non-interchangeable when used in a double station having correspondingly-shaped apertures, substantially as shown and set forth.

4. In a revolving double conductor having tubes a b , provided at their lower end with the projecting plates z z , the combination therewith of a stationary partition having a series of openings, v , therein, each separated by the tie u' , its upper surface being rounded or beveled, substantially as shown and set forth.

In testimony whereof I have affixed my signature in presence of two witnesses.

FRANK W. GRISWOLD.
